UNITED STATES PATENT OFFICE.

LEWIS HALLOCK NASH, OF SOUTH NORWALK, CONNECTICUT, ASSIGNOR TO
THE NATIONAL METER COMPANY, OF NEW YORK, N. Y.

GAS-ENGINE.

SPECIFICATION forming part of Letters Patent No. 578,112, dated March 2, 1897.

Application filed June 17, 1891. Serial No. 396,561. (No model.)

To all whom it may concern:

Be it known that I, LEWIS HALLOCK NASH, of South Norwalk, in the county of Fairfield and State of Connecticut, have invented a new and useful Improvement in Gas-Engines; and I do hereby declare the following to be a full, clear, and exact description of the invention, such as will enable others skilled in the art to which it appertains to make and use the same.

10 My present invention consists of certain novel parts and combinations of parts constituting an improved gas-engine and parts of a gas-engine.

15 In the accompanying drawings, Figure 1 is a vertical section through a gas-engine involving my present invention. Fig. 2 is a side view of the engine, partly in section, through the exhaust-valves. Fig. 3 is a similar view from the opposite side, partly in section, 20 through the mixing and admission valves. Fig. 4 is an end view of the fly-wheel, showing parts of the governing device. Fig. 5 shows modification of a part of the governing device.

25 I will now describe the construction of the engine shown in the accompanying drawings, which contains in total combination all the novel features of my present invention, each in one of the many forms in which it may be 30 practically embodied, and that the form which I at present prefer to employ.

2 is the base of the engine supporting the cylinders 3 and 3^a.

35 5^b is a double-ended piston, one end, 5, working in the cylinder 3, and the other end, 5^a, working in the cylinder 3^a.

40 4 is a shaft set in suitable journals, about which the rocking arm 6 oscillates. This rocking arm at one end is connected with the crank-pin 8 by means of the link 9.

10 is the power-shaft.

11 is a fly-wheel.

12 is the weight of the governing device operated by centrifugal force, occupying a 45 position determined by the speed of the engine.

14 and 14^a are the clearance-spaces at the ends of the cylinders 3 and 3^a, respectively.

Referring to Fig. 2, which shows the exhaust-valves connected with the power-cylinders 3 and 3^a, 15^a is a chamber connected

with the clearance-spaces 14^a, and 15 is a chamber connected with the clearance-spaces 14. 16 and 16^a are the valves controlling communication between the chambers 15 and the air and 15^a and the air. Through the ports controlled by the valves 16 and 16^a the waste gases after combustion are exhausted, passing through the ports 17 and 17^a to the open air. These valves 16 and 16^a are each attached to a guide or stem 18 and 18^a, carried in guides 19 and 19^a and surrounded by springs 20 and 20^a, constantly operating to keep said valves down upon their seats. 21 is a crank-disk, to which the rods 22 and 22^a 65 are attached. The outer ends of these rods travel in the guides 19 and 19^a and alternately abut against the stems 18 and 18^a, forcing the valves 16 and 16^a away from their seats. The crank-disk 21 is connected to an eccentric 39, attached to a stud 40, set in suitable bearings. This stud 40 carries the gear-wheel 60, which meshes with the gear-wheel 42, of one-half its size, which is attached to the main shaft 10.

75 Referring to Fig. 3, which is a side view of the engine from the opposite side, 27 and 27^a are passages connecting, respectively, with the clearance-spaces 14 and 14^a, Fig. 1. 28 and 28^a are valves set upon stems 29 and 29^a, 80 and constantly forced toward their seats by springs 30 and 30^a. 31 and 31^a are perforations through which atmospheric air may pass to the valves 28 and 28^a through the passages 27 and 27^a, when said valves are raised 85 and there is a partial vacuum present in the power-cylinder. 32 and 32^a are valves provided with stems 34 and 34^a and with springs 33 and 33^a constantly tending to force said valves on their seats. The ends of the stems 90 34 and 34^a are provided with inclined pieces 35 and 35^a. 36 is a rocking arm pivoted at 37. 38 and 38^a are rods connected with said rocking arm 36 and alternately abutting against the inclined stem ends 35 and 35^a. 95 The ends of these rods are also shown in the drawings as inclined, the inclination of the rods corresponding substantially with the inclination of the stem ends 35 and 35^a. The rocking arm 36 is connected with eccentric 23, 100 attached to the stud 24, to which is attached the gear-wheel 25, meshing with the teeth of

- the gear-wheel 26, of one-half its size. Gear-wheel 26 is connected with the main shaft 10 of the engine. 43 is a rod carrying the fingers 44 and 44^a, radially projecting therefrom. 5 The arms 38 and 38^a respectively rest on the fingers 44 and 44^a, and when the rod 43, carrying these fingers, turns in its bearings 45 and 45^a the ends of the rods 38 and 38^a are more or less raised, so that they sooner strike 10 against the beveled stem ends 35 and 35^a and remain in contact therewith for a longer period of time, thus holding the valves 32 and 32^a open a longer or shorter time. The openings 46 and 46^a communicate with a suitable 15 reservoir containing gas or other fuel, the admission of which to the power-cylinders is thus controlled. The shaft 43 is by any suitable mechanism attached to the governor device.
- 20 Fig. 4 shows one form of connecting mechanism which may be employed. 47 is a sleeve sliding along the power-shaft 10, in or out, to a position corresponding with the position of the governor-weight 12 by connection common in engines. The sleeve 47 is connected with the shaft 43 by bell-crank lever 49 and link 48. On the end of the bell-crank lever is a pin 50, working in a groove on the sleeve 47. By this connection the position of the 25 rod 43 and its fingers 44 and 44^a is determined, and by said fingers the elevation of the ends of the rods 38 and 38^a is controlled.
- 20 The operation of the engine illustrated may thus be described: The engine shown is of 35 what is commonly known as the "four-cycle" type. In these engines an explosion occurs in the power-cylinder at one stroke, the waste gases are discharged at the next stroke, the new charge is drawn in on the following 40 stroke, and the charge is compressed by the last stroke. In this type of engine as heretofore constructed there has been but one impulse at every double revolution of the crank. In the engine illustrated, however, although 45 of the four-cycle type having a single crank, there is an impulse at every revolution of the crank.
- Referring to Fig. 3, gas is admitted through the opening 46 46^a and air through the perforations 31 and 31^a. Whenever there is a partial vacuum within one of the power-cylinders caused by the motion of the piston after exhaustion, the valve 28 or 28^a will rise from its seat, permitting air to be drawn into the 50 corresponding cylinder through the port 31 or 31^a. At the same time the rod 38 or 38^a forces the corresponding gas-inlet valve 32 or 32^a open, permitting gases to be drawn in with the air, forming a combustible mixture. 55 As the piston returns this valve is closed and the charge compressed. Explosion of the combustible charge then takes place by any suitable form of igniting device. I have not shown an igniter because it forms no 60 part of my present invention, and several efficient forms are well known to those skilled in this art. As the piston after explosion re-

turns the exhaust-valve 16 or 16^a is opened, and the waste gases are forced therethrough and through the port 17 or 17^a to the air, 70 these exhaust-valves being controlled by the crank-disk 21. A consideration of the construction will show that these operations occur alternately in the cylinders 3 and 3^a, so that while the cylinder 3 is compressing its 75 charge the cylinder 3^a is exhausting, and while the cylinder 3 is exploding the cylinder 3^a is drawing in a new charge, and while the cylinder 3 is exhausting the cylinder 3^a is compressing, and while the cylinder 3 is drawing in a new charge the cylinder 3^a is exploding. Thus it will be seen that the explosions occur alternately and that there is an explosion for every revolution of the crank.

In Fig. 3 I have shown the inclinations of 85 the stem ends 35 and 35^a and the rod ends 38 and 38^a the same, so that assuming that the fingers 44 and 44^a be of the same length and similarly set both cylinders will at all times work under the same conditions, both increasing and decreasing in power simultaneously. Instead of so arranging, however, these ports I may, and indeed I prefer to, arrange them so that the cylinders will increase and diminish power unequally, and this in any desired 90 proportion or relation. One means of accomplishing this result is shown in Fig. 5. In this figure the stem end 35^b is substantially like the stem end 35 in Fig. 3. The rod end 38^b in Fig. 5, however, is changed, so that 95 when it has fallen a certain distance it no longer makes connection with the stem end 35^b, and thus the cylinder 3 is thrown out of work. The stem end 35^c is formed with a vertical part above the tapered part, and the 100 rod end 38^c, connecting therewith, has a vertical part below the tapering part, so that as the rod end 38^c falls it continues for a long time to open the valve 32^d wide, so that the cylinder 3^a receives a full charge; but when the 105 tapering part of the rod 38^c comes in contact with the tapering part of the stem end 35^c the rise and fall of the rod 38^c will increase or 110 diminish the charge under which the cylinder 3^a is working. If these parts be properly 115 proportioned, therefore, the cylinder 3^a will continue to receive a full charge while the cylinder 3 is receiving a diminished charge. This condition may continue until the engine is working under one-half load, when the cylinder 3 is entirely thrown off and all the work 120 is being done by the cylinder 3^a. If it is desirable to further diminish the power of the engine, the depression of the end of the rod 38^c accomplishes this, as at that time the inclined ends of these parts are in contact, and any change of position of the rod affects the 125 charge delivered to said cylinder. The advantage of this arrangement, among other things, is that a more economical consumption of the fuel is obtained because one of the cylinders is always working with full charge whenever, preferably, the engine is working at half-load or more. This feature 130

of my invention is applicable not only to four-cycle engines, but also to any form of double-acting or two-cylinder engines operated by any suitable motive power. Any other arrangement of parts may be employed which will cause the cylinder to increase or diminish power at different rates or at different times in any desired manner, as will be readily understood.

10 Referring to Fig. 1, it will be seen that the crank-pin and its connections are moving toward the left while the piston and its connections are moving toward the right. The movement of these parts in opposite directions simultaneously balance one another, and assuming that they are the same weight no momentum is communicated to the support of the engine, or if they be of different weights the momentum communicated is only that 15 due to the difference. As gas-engines are very frequently placed in upper stories of buildings, this feature in a horizontal engine is of great value and materially extends the usefulness of the device.

20 25 In the foregoing specification I have incidentally referred to a few of the modifications which might be adopted in practicing my invention, but I have not endeavored to specify all the modifications which might be employed, the object of this specification being to instruct persons skilled in the art to practice the several novel features of my invention in their present preferred forms and to enable them to understand their nature, and 30 35 I desire it to be distinctly understood that mention by me of a few modifications is not in any way intended to exclude others not referred to, but which are within the spirit and scope of my invention, and that in so far as 40 my invention consists of novel methods these are independent of the mechanism described or of any particular mechanism.

45 As I have before remarked, many of the combinations and details illustrated and above described are not essential to the several fea-

tures of my invention separately and broadly considered. All this will be indicated in the concluding claims, as in any given claim the omission of an element or of the particular features of the elements mentioned is intended to be a formal declaration of the fact that the omitted elements and features are not essential to the invention therein covered. 50

Having thus described a machine embodying in preferred forms all the several features 55 of my present invention in combination, what I separately claim, and desire to secure by these Letters Patent, is the following:

1. In a gas-engine the combination of a plurality of power-cylinders with their respective pistons, a governor and mechanism operated by said governor for automatically varying the power developed when both cylinders are in action by changing the power developed in one cylinder without changing the 60 power developed in another.

2. In a gas-engine, the combination of a plurality of power-cylinders with their respective pistons, a governor and mechanism operated by said governor for automatically varying the power developed when both cylinders are in action by changing the power developed in one cylinder throughout its entire 70 range without changing the power developed in the other. 75

3. In a gas-engine the combination of a plurality of power-cylinders with their respective pistons, a governor for automatically controlling the power developed in a plurality of said cylinders and mechanism operated thereby for varying the power developed in the different cylinders successively and not simultaneously. 80

In testimony whereof I have signed this specification in the presence of two subscribing witnesses.

LEWIS HALLOCK NASH.
